UNITED STATES PATENT OFFICE.

WILLIAM M. ROGERS, OF WHITESVILLE, KENTUCKY.

TICKET CUTTER.

Application filed April 26, 1926. Serial No. 104,712.

This invention relates to improvements in ticket cutters, and provides a convenient retainer and cutter combined, particularly adapted to railroad tickets, and an equal advantage in practically all classes of transportation ticket forms.

One of the foremost objects of the invention, is that it was primarily designed to specifically accommodate a special ticket form, also devised by me, and the application for a patent on which is being filed at the same time as this one, upon the 26th day of April, 1926, Serial Number 104,711.

My invention comprises a metal framework, preferably of an aluminum casting, and arranged so as to accurately guide the ticket form, a clamping and cutting arrangement for shearing said form in a manner so as to indicate the station and form desired upon the passenger and auditor's ticket. The particular advantage of this cutter is to greatly facilitate the work of issuing tickets to passengers by the agent, and with the aid of the ticket form previously mentioned, the combination thereof will be found to be very effective in this particular branch of railroad service.

I desire to reserve the privilege to make certain minor changes in the details of construction, if same should become a necessity in the practical development of the device for the market, but without a departure from the scope of what is herein described and claimed.

The invention comprises further advantages, all of which will be clearly pointed out in the following detailed description with reference to similar numerals in the accompanying drawings.

With reference to the drawings:

Figure 1 is a normal size plan view of the device, and showing the ticket form therein, also a slight portion broken away upon the upper part of the view.

Figure 2 is an end elevation of Fig. 1, with indicating pointers and ticket form omitted.

Figure 3 is a similar view to Fig. 1, with the cap members omitted, and the dotted lines show the pads upon the underneath thereof.

Figure 4 is a partial front elevation and section, taken on the line, A—A of Fig. 3.

Figure 5 is a plan view of one of the cap members.

Figure 6 is an enlarged elevation of one of the indicating pointers and its relation to the cutter bar, the latter being in section, and the view taken on line B—B of Fig. 1.

Figure 7 is a reduced isometric view of the complete device.

Figure 8 is a normal size plan view of the cutter bar, and portions thereof broken away, indicating the grooves therein.

Figure 9 is an enlarged end elevation of the cutter bar, and part in section, showing one of the studs riveted therein.

Figure 10 is an enlarged elevation of one of the studs.

The invention comprises properly a framework, preferably of an aluminum casting, and having a top plane surface as shown, and indicated by the numeral 1. Extending upward and forming a part thereof, are the walls 2, and which enclose the two ends and portions of one of the sides, forming an opening 3 therein which is to facilitate taking the ticket from the device after it has been sheared. The metal at two of the corners of the framework is somewhat enlarged, as at 4, thus avoiding sharp corners thereon, and forming substantial reinforcement at said location.

In order to provide elevation of the framework so that it will be convenient for quick operation, pads or legs 5 are a part of said framework, and located where shown. This will be clearly seen by referring to Fig. 3. In order to provide suitable means for connecting the device to the desired location, ears or lugs 6 also form a part of the framework, and have extended portions 7 underneath thereof, and their bottom portions being on the same plane as the pads 5, and serving the same purpose in addition to reinforcing said ears. Countersunk holes 8, and lugs 9 in the ears 6 are shown. Said holes are for the accommodation of similar shaped head screws, which may be for wood or metal, and said lugs for the purpose of retaining coil springs which will be presently explained. It will be noted that the metal of the framework is extended over both sides thereof, as at 10, and thereby adds strength to the general structure.

A cutter bar 11 is provided, and is composed of a high grade suitable steel for this purpose, and provided with a cutting edge 12, which is effected by cutting the recess 13 into the metal, as will be seen in Fig. 6. 110

Concaved portions are provided within the sides of said bar, as shown at 14, to guide and retain the similar shaped portions 15 of the indicating pointers 16, which are composed of a suitable class of spring steel for the purpose. The point 17 of one of said indicators is sharpened to a cutting edge, and is for the purpose of indicating the station upon the ticket form as mentioned, while a similar point 18 is formed upon the other indicator for indicating the form desired upon said ticket, and is likewise sharpened. Said indicators will slide freely upon said cutter bar and will remain in an accurate position at any location upon which they are released.

The cutter bar 11 is supported upon coil springs 19, one being at each end thereof, and being of equal tension, and their lower ends retained by lugs 9 respectively, of the ears 6. The upper ends of said coil springs have bearing against the ends of said bar, and are retained in position as shown by steel studs 20, which are composed of riveting stock, and are originally as shown in Fig. 10, with shanks 21. Countersunk holes 22 in bar 11 for said studs, permit said shanks to be riveted as shown at 23, the top surfaces thereof being dressed to a smooth surface, and flush with the top surface of said bar as indicated. Openings 24 in the walls 2 of the general framework are provided to permit the action of the ends of the cutter bar 11, and indentations 25 in said bar for aiding and guiding said action. Cap members 26, preferably of aluminum casting are provided, and form suitable stops for said bar. Lugs 27 project as shown, and are a part of the main framework, and are provided with threaded holes 28 to receive screws 29 of similar threads. Holes 30 in caps 26 are for the passage of said screws, and retain same substantially as shown.

For complete illustration of the manner in

which the device is used; it is assumed that a passenger has purchased a ticket to the station, Cecilia, and the form desired is a single trip, the ticket is placed into the device as shown in Fig. 1, and the indicating pointers moved to the positions as indicated respectively, the cutter bar is then pressed down upon the ticket and one portion is sheared off from the other. The passenger ticket will then indicate the station and form desired by indentations, while the auditor's ticket will show likewise indications by projections immediately opposite the indentations, and thus with any form or station upon the ticket, desired. Said ticket is arranged so that either side thereof may be placed into the device first, and thereby reverse the indentations and projections whenever preferred. After releasing the cutter bar the coil springs will automatically elevate it to normal position as seen.

The advantage of my ticket form is explained in the application for same, and in connection with this cutting device makes a most desirable and effective arrangement for the purpose set forth.

Having thus described my invention what I claim as new is:

In a ticket cutter as described, a framework comprising a top plane surface adapted to receive a special ticket form, a horizontally disposed cutter bar supported upon vertically arranged coil springs, the latter bearing upon extended end portions of said framework respectively, an opening in each of the ends of said framework to permit the action of said cutter bar, a cap disposed over each of the aforesaid openings and connected to the framework, also means for elevating said top plane surface from the plane upon which the general framework is adapted to be used.

In testimony whereof I affix my signature.

WILLIAM M. ROGERS.
